UNITED STATES PATENT OFFICE.

FREDERICK W. HALL, OF BROOKLYN, NEW YORK.

DESIGN FOR A PUZZLE BOX OR CASE.

SPECIFICATION forming part of Design No. 25,964, dated August 18, 1896.

Application filed June 30, 1896. Serial No. 597,647. Term of patent 31 years.

To all whom it may concern:

Be it known that I, FREDERICK W. HALL, a citizen of the United States, residing at the city of Brooklyn, in the county of Kings and State of New York, have invented and produced a new and original Design for Puzzle Boxes or Cases, of which the following is a specification, reference being had to the accompanying drawings, forming a part there-
of, in which—

Figure 1 is a plan view of my improved design for puzzle boxes or cases; and Fig. 2, a section on the line 2-2 thereof, these two views being necessary to fully illustrate my design.

The leading feature of my new and original design for puzzle boxes or cases consists of a bottom A, the sides a , and the ends a^2 , and the interior arrangement of the box or casing, which is substantially as follows: Arranged in the opposite corners at one end thereof are two segmental or curved walls B, whereby triangular chambers C are formed, and adjacent to said end is a segmental or curved wall D, at each end of which is a passage d, and adjacent to the wall D are two segmental or curved walls E, said walls E being curved in a direction opposite to the curve of the wall D, and the walls E connect with the opposite sides of the box or casing, and between the same is an open space or passage F. Two other walls G, of slightly-greater curvature than the walls E, are arranged adjacent thereto and connect with the sides of the box or casing, and are separated by a space g, and two walls H, similar to the walls G, are also provided, between which is a space or pas-

sage h, and adjacent to the walls H are two inwardly-directed chambers K, which are similar in form and which open inwardly, and which project from the side walls on each side about one-third of the distance across the box or casing, and between said chambers K and the adjacent end of the box are two curved walls M, the convex sides of which are directed toward the chambers K, and the curved walls M also connect with the opposite sides of the box or casing, and between the same is a passage m, and along the longitudinal center, at predetermined points between the chambers K and the walls E and G, are placed vertical pins O, having heads P.

As thus constructed it will be seen that the box or casing is divided into various communicating compartments by the various walls placed therein, with the exception of the compartments C, which are closed, and that said walls, while being all curved, are slightly irregular in form, and the entire device is also rectangular in form.

Having fully described my invention, I claim as new and desire to secure by Letters Patent—

The herein-described design for puzzle boxes or cases, said design being substantially as set forth.

In testimony that I claim the foregoing as my invention I have signed my name, in presence of the subscribing witnesses, this 27th day of June, 1896.

FREDERICK W. HALL.

Witnesses:

W. W. HILL,
CHARLES S. ROGERS.
